UNITED STATES PATENT OFFICE.

PHILLIP HIEN, OF CHICAGO, ILLINOIS, ASSIGNOR TO DAVID S. WEGG, OF SAME PLACE.

DESIGN FOR A DRAW-HEAD FOR CAR-COUPINGS.

SPECIFICATION forming part of Design No. 33,752, dated December 18, 1900.

Application filed November 24, 1900. Serial No. 37,682. Term of patent 14 years.

To all whom it may concern:

Be it known that I, PHILLIP HIEN, a citizen of the United States, and a resident of Chicago, in the county of Cook and State of Illinois, have invented and produced a new and original design for a Draw-Head for Car-Couplers, of which the following is a specification, reference being had to the accompanying drawings, and to the letters of reference 5 marked thereon, which form a part thereof.

In said drawings, Figure 1 is a front elevation of a draw-head embodying my design. Fig. 2 is a side elevation of the same. Fig. 3 is an elevation of the side opposite that 15 illustrated in Fig. 2. Fig. 4 is a top plan view of the same. Fig. 5 is a section taken on line 5 5 of Fig. 1. Fig. 6 is a section taken on line 6 6 of Fig. 1.

As shown in the drawings, my design is for a 20 draw-head of the type known as the Master Car-Builders' draw-head and is hollow and provided on its outer end, on one side of the axis, with apertured lugs a^2 , designed to receive between the same a swinging knuckle. Said draw-head is provided in the outer end 25 with an opening designed to receive the tail of such a knuckle. On the inner wall of the draw-head, on the same side as said lugs, is provided a rearwardly-directed rib B, integral 30 with the side wall and forming a rearwardly-directed hook, as indicated in Fig. 5.

a^2 a^3 indicate longitudinal upwardly-extending webs on the inside of the draw-head integral with the bottom thereof, which extend forward to the opening in the front end. 35 Said webs are approximately parallel each to each. A web a^4 , corresponding to the web a^2 , depends from and is integral with the upper wall of the draw-head, and a transverse 40 web a^5 extends from each of said webs a^2 and a^4 to the side wall of the draw-head adjacent to the hook or tug B. The web a^5 at its front end is slotted, as indicated in Figs. 1 and 5, and a corresponding slot is formed in the

outer end of the draw-head in the same plane 45 therewith.

The top of the draw-head is provided with an aperture extending downwardly therethrough along the inner side of the web a^3 . Said aperture is surrounded by an upwardly-directed flange C, integral with the top of the draw-head, and a corresponding flange is provided on the inner side of the draw-head, providing an elongated vertical socket, as shown in Figs. 4 and 6. Flanges c c' , integral 50 with the top of the draw-head, extend rearwardly, the flange c being integral with the rear side of the flange C. The rear side of said draw-head is provided with an upwardly-projecting shoulder surmounted by the flange 55 c^2 , which connects integrally with the flanges c c' . A projection c^3 extends laterally and horizontally from the top flange c and provides on its lower side a downwardly-projecting shoulder, as more fully illustrated in Figs. 60 1, 2, and 4.

The material or essential features of my design are a draw-head for car-couplers provided on one of its inner side walls with a rearwardly-directed hook, a downwardly-extending socket in the top of the draw-head, one side of the same being in alinement with a web within the draw-head, and on one side of said socket, on its upper end, a horizontal 70 projection.

Having now described my design, what I claim as new, and desire to secure by Letters Patent, is—

The design for a draw-head for car-couplers, substantially as shown and described. 80

In witness whereof I have hereunto subscribed my name in the presence of two subscribing witnesses.

PHILLIP HIEN.

In presence of—
CHARLES W. HILLS,
L. J. DELSON.
